UNITED STATES PATENT OFFICE.

HUNTER SMITH, OF BECKLEY, WEST VIRGINIA.

RAIL CLAMP.

Application filed March 29, 1924. Serial No. 702,875.

To all whom it may concern:

Be it known that I, HUNTER SMITH, a citizen of the United States, residing at Beckley, in the county of Raleigh and State of 5 West Virginia, have invented certain new and useful Improvements in Rail Clamps, of which the following is a specification.

This invention relates to rail clamps or fasteners, and more particularly to clamps 10 especially adapted for use in mines and similar situations where temporary rails are employed.

Under the conditions prevailing in mines, especially coal mines, it is often necessary, 15 or desirable, to extend an existing track by means of temporary rails laid on their sides and forming a lap joint with the permanent rails.

The object of the present invention is to 20 provide a clamp for holding such temporary rails in place, which clamp shall be of the simplest possible construction, consisting of the minimum number of parts, and which, at the same time, shall perform its 25 function in a satisfactory and effective manner. More specifically, a subsidiary object of the invention is to avoid the necessity for using any specially constructed wedge plates or the like, and to this end, I so design the 30 parts that an ordinary railroad track spike may be employed as a wedge or key. One such spike and a single clamp member are the only pieces required to form my improved clamp.

35 In order that the invention may be readily understood, reference is had to the accompanying drawing, in which:—

Figure 1 is a transverse vertical section through a permanent or tread rail and a 40 temporary or extension rail, held together by means of one of my improved rail clamps;

Figure 2 is a plan view thereof;

Figure 3 is a perspective view of the 45 clamp member itself; and

Figure 4 is a perspective view of the key or wedge employed.

Referring to the drawings in detail, 1 designates the ordinary tread rail forming 50 part of the permanent track, and 2 indicates the temporary or extension rail. As clearly shown in Figure 1, this extension rail is used resting upon its side, with its head lying between the head and base of the tread rail 1.

55 These two rails are supported upon my improved clamping member, which com-

prises a plate 3, on which the base of the tread rail rests, and an upstanding extension 4, at one end of the plate, shaped and positioned to engage the bottom of the base 2^a of the extension rail. Preferably, the upper end of the extension 4 is prolonged and bent over to form a lip or flange 5, adapted to overhang the upper edge of the base 2^a of the extension rail.

Adjacent the other end of the plate 3, and extending upwardly therefrom, is a hook portion 6, preferably formed integral with the plate, and having a nose 7, spaced from the plate a sufficient distance to receive between itself and the plate, the edge of the base flange 1^a of the tread rail 1.

Formed on the under side of the hooked portion 6, between the nose 7 and body of the hook, is a key-way 8, most clearly shown in Figure 3, which key-way is shaped to receive a wedge or key 9. By reference to Figure 4, it will be seen that this wedge or key is in the shape of a railroad spike, and in practice, an ordinary spike, such as is in common use for fastening the rails to the ties, is employed. Thus, the necessity for fabricating any specially formed key or wedge is avoided and not only is the cost of the rail spikes employed almost negligible, 85 but a supply of such spikes is usually available in the mine and therefore, they can be readily obtained at any time.

As will be seen from an inspection of Figures 1 and 2, after the rails and clamping member are assembled, as shown, the key or spike is inserted in the key-way 8 and driven into such key-way, entering between the body of the hook and the edge of the base flange 1^a of the tread rail. By this means, in combination with the upstanding portion 4, the two rails are clamped firmly together, and it will be noted that the nose 7 of the hook 6 overlies the base flange of the rail, thus preventing vertical movement thereof.

It will be understood that my improved clamping member is made either by casting or forging in a single piece, and that this piece, together with one ordinary spike, is all that is required to secure the rails together at any desired point.

What I claim is:—

1. A rail clamp comprising a plate adapted to support a tread rail resting on its base, and an extension rail lying on its side, with its head between the head and base of

the tread rail, said plate being provided at one end with an upstanding portion adapted to engage the bottom face of the base of the extension rail, and having adjacent the other end a hook portion arranged to overlie the base of the tread rail, and a wedge member adapted to be driven in between the said hook portion and the edge of the base of the tread rail where it passes beneath such hook portion.

2. A rail clamp comprising a plate adapted to support a tread rail resting on its base, and an extension rail lying on its side, with its head between the head and base of the tread rail, said plate being provided at one end with an upstanding portion adapted to engage the bottom face of the base of the extension rail, and having adjacent the other end a hook portion arranged to overlie the base of the tread rail, the under surface of said hook portion having a key-way formed therein, and a key or wedge shaped to fit said key-way, and adapted to be driven

therein so as to enter between the hook portion and the edge of the base of the tread rail and thus lock the parts together.

3. A rail clamp comprising a plate adapted to support a tread rail resting on its base, and an extension rail lying on its side, with its head between the head and base of the tread rail, said plate being provided at one end with an upstanding portion adapted to engage the bottom face of the base of the extension rail, and having adjacent the other end a hook portion constructed to receive between itself and the plate the base flange of the tread rail, and a key or wedge in the shape of an ordinary rail spike adapted to be inserted under said hook portion in such manner as to bear at one side against said hook portion, and at the other side against the edge of said base flange of the tread rail.

In testimony whereof I affix my signature.

HUNTER SMITH.
